ABSTRACT OF THE DISCLOSURE

A core-type transformer for an AC arc welder in which the primary and secondary windings are aluminum strips interleaved with woven glass tape as the dielectric. The woven glass tape acts almost exclusively as a mere spacer. A second core is movable into and out of the window of the wound core. The second core is mounted on a vertical shaft journaled in a pair of brackets on horizontal reaches of the wound core. The vertical shaft is held in V-shaped seats in the brackets by relatively stiff keeper plates bearing against the opposite side of the shaft. The shaft extends through a sheet metal top cover and is capped by a pointer and handle for rotating the shaft and second core. Pin keys in the shaft above and below the top cover hold flanged locks. A cam on the handle compresses the top cover between the locks when the handle is pivoted downwardly. A table on the top cover indicates the output amperage of the transformer as the pointer moves and includes a set of colored bands, the colors of which correspond to American Welding Society code colors of some welding electrodes to be used with the welder.

BACKGROUND OF THE INVENTION

This invention relates to transformers for AC arc welders. It has particular, but not exclusive, application to a core-type transformer having a second core movable into and out of the window of the wound core.

Transformers for so-called "limited service" arc welders provide a variable low voltage high amperage AC output. One method of providing a stepless variation in amperage over a relatively extended range is to utilize a core-type transformer having primary coils and one set of secondary coils wound on one vertical leg of the frame and a second set of secondary coils, or reactors, wound on the other vertical leg of the frame. The individual coils of each set of coils are electrically connected in series, and the first set of secondary coils is electrically connected in series to the reactors. A low amperage outlet plug may be electrically connected to the first set of secondary coils through the reactor coils and a high amperage outlet plug may be electrically connected to the first set of secondary coils through a single reactor coil. If more than two reactor coils are provided, other plugs may also be provided. A stepless range of amperage output is provided at each plug by a second core which is movable into and out of the window of the wound frame. The movable core may be simply a laminated block nearly the height of the window and may be mounted on a vertical shaft for rotation into and out of the window. As the movable core is moved into the window of the wound core it acts

2

as a magnetic shunt, which decreases the output of the reactor coils.

Certain problems inhere in a transformer of this design. A particularly compact and efficient coil design is required. Furthermore, the rotational and vibrational strains which are physically and magnetically exerted on the movable core require particularly rattle-free and wear-resistant bearings for the movable core shaft, an easy means for moving the core into and out of the wound frame window and a convenient yet effective method for locking the shaft at any desired position. Finally, the stepless control requires a convenient method of indicating the output amperage at any position of the movable core and a method of correlating this information with the choice of an appropriate electrode for any given job within the capabilities of the transformer.

One of the objects of this invention is to provide a welding transformer which meets the foregoing requirements better than presently known welding transformers.

Other objects will occur to those skilled in the art in the light of the following description and accompanying drawing.

SUMMARY OF THE INVENTION

In accordance with this invention, generally stated, a variable welding transformer is provided having primary coils and secondary coils, each of which includes a coiled flat strip of electrically conductive material, successive reaches of which are separated by a woven glass tape. The weave of the glass tape is relatively loose, and therefore the coils are effectively provided with an air dielectric.

The primary coils and at least some of the secondary coils are positioned on parallel legs of a stationary core, or frame. A second, movable, core is mounted on a shaft, which in turn is rotatably mounted on the frame by a novel support bracket. The support bracket includes a horizontal plate secured to a horizontal reach of the frame. An aperture is provided in the horizontal plate. A V-shaped seat at one margin of the aperture receives a curved surface of the shaft, and a generally vertical keeper plate biases the shaft into engagement with the seat. In the preferred embodiment, two support brackets are provided, one on each horizontal reach of the frame, and the shaft is journaled to restrict its vertical motion.

Novel means are also provided for rotating the shaft and movable core, locking the shaft at a desired position, and indicating an appropriate position of the movable core for welding operations utilizing particular output terminals and electrodes and for particular work applications.

The rotating and locking means are attached to a section of the shaft extending through a top cover on the welder, and include a cam pivotally mounted on the shaft and a handle secured to the cam. The cam is movable from a release position to a lock position, in which the cam holds the upper cover tightly against a lower bearing surface on the shaft below the upper cover.

In the preferred embodiment the lower bearing surface includes a closure piece which rests on an abutment on the shaft. An upper closure piece is also provided, between the cam and the upper cover. Each closure piece has a larger outer diameter than the aperture in the upper cover and is provided with an aperture through which

the shaft extends, so that the cam compresses the upper cover between the upper and lower closure pieces. Also in the preferred embodiment the upper closure piece is a cupped lock, the lip of which rests on the upper cover, and the lock and cam are both connected to the shaft by a pivot pin extending through the shaft above the upper cover.

The indicating means include a pointer mounted on the upper end of the shaft for rotation therewith and a number of colored bands on the upper cover, the color of each band corresponding to a code color of a welding rod. In the preferred embodiments, each colored band is divided into segments, and each segment represents a recommended electrode size for use at the amperage of one of the output terminals.

BRIEF DESCRIPTION OF THE DRAWINGS

In the drawings, FIG. 1 is a view in front elevation, partially cut away, of a welder transformer of this invention;

FIG. 2 is a view in side elevation, partially cut away, of the welder transformer shown in FIG. 1;

FIG. 3 is a top plan view of the welder transformer shown in FIGS. 1 and 2;

FIG. 4 is a sectional view taken along the line 4—4 of FIG. 2;

FIG. 5 is a sectional view taken along the line 5—5 of FIG. 1;

FIG. 6 is a sectional view also taken along the line 5—5 of FIG. 1, partially cut away;

FIG. 7 is a view in side elevation, partly in section, of the rotating and locking means of the welder shown in FIGS. 1—6, with a pointer housing removed;

FIG. 8 is a view in side elevation of the pointer housing; and

FIG. 9 is a circuit diagram of the welder transformer shown in FIGS. 1—8.

DESCRIPTION OF THE PREFERRED EMBODIMENT

Referring now to the drawings, reference numeral 1 indicates one illustrative embodiment of welder transformer of this invention. The transformer 1 includes a housing 2, a wound core 3, a movable core assembly 6, a rotating and locking mechanism 8 and an indicating means 10.

The housing 2 includes a pair of base brackets 20, a guard screen 21 welded to the base brackets 20, a pair of sheet metal side panels 22, a sheet metal piece 23 which is bent to form a front panel 24 and a sloping top panel 25, and a rear panel 26. The side panels 22 are screwed to the base brackets 20 and to wings on the sheet metal piece 23.

Mounted on the inner face of the front panel 24 and extending through it are an on/off switch 9, a ground cable 11, a "high" outlet plug 12 and a "low" outlet plug 13. The outlet plugs 12 and 13 are alternative receptacles for a welding electrode cable. Mounted on the back panel 26 are a fan 14 which draws air through the housing and an outlet box 15 for a power cord 16.

The wound core 3 includes a rectangular core or frame 30 welded to the base brackets 20 through the guard screen 21. The frame 30 may be made of ordinary L-laminations. The upper and lower horizontal reaches of the frame 30 are provided front and back with stiffener laminations 31, and the frame and stiffeners are held together by through bolts at the corners of the frame 30.

Mounted on one of the vertical legs of the frame 30 are a set of four primary coils 32 and a set of two secondary coils 33, positioned between the primary coils 32 and the frame 30. The secondary coils 33 are spaced from the vertical leg of the frame 30 by four corner spacers 34. The primary coils 32 are spaced from the secondary coils 33 by spacer blocks 35 around the outboard side of the coils and by a strip of insulation 36 at the inboard side of the coils.

Two further secondary coils or reactors 37 and 38 are mounted on the other vertical leg of the frame 30. The reactors 37 and 38 are spaced from the vertical leg by four spacers 39, which are essentially the same as the spacers 34 on the other leg.

Each of the coils is formed of a continuous strip of bare aluminum 40 interleaved with woven glass tape 41 having a slightly greater width than the aluminum strip. The inner ("start") end of the top primary coil, the outer ("finish") end of the aluminum strip of the bottom primary coil, and both the start and finish ends of the intermediate coils are formed into leads by bending the aluminum strip flat on itself and taping the fold flat against the coil with pressure sensitive polyester tape. A suitable tape for this purpose is sold by Minnesota Mining & Manufacturing Company as #55 "Scotch" polyester pressure sensitive tape. All of the other leads are formed by cold welding a copper strip lead transverse of the aluminum strip, near its end. "Scotch" #55 tape is also used to hold these ends and leads flat. The primary coils 32 and the reactor coils 37 and 38 are wrapped with a length 42 of "Scotch" #69 tape, around their outer faces.

The leads are connected as follows. The start lead 45 of the bottom primary coil and the finish lead 46 of the top primary coil are electrically connected to the on/off switch 9, and the other primary start leads 43 are each cold welded to the primary finish lead 44 of the coil below. The start lead of the lower secondary coil 33 is cold welded to the finish lead of the upper secondary coil 33, the finish lead 47 of the lower secondary coil is connected to the ground cable 11, and the start lead 48 of the upper secondary coil 33 is electrically connected to the finish lead 49 of the lower reactor coil 37. The start lead 50 of the lower reactor 37 and the finish lead 51 of the upper reactor 38 are both connected to the "high" output plug 12. The start lead of the upper reactor 38 is electrically connected to the "low" output plug 13.

It will be seen that the primary coils 32 and the first set 40 of secondary coils 33 are each connected in series and that the secondary coils 33 are coupled to the output plugs 12 and 13, respectively, through the lower reactor coil 37 and through both reactor coils 37 and 38 in series.

The fan 14 is electrically connected to the same terminals of the on/off switch 9 as the primary leads 45 and 46, and the power cord 16 is electrically connected to the other side of the switch 9, so that the fan and primary coils are both activated when the cord 16 is plugged into a source of single phase 230 volt alternating current and the switch 9 is turned on.

Merely by way of illustration, the coils may be made of the following materials and may have the following dimensions:

Primary coils 32 (each) -- 39 turns of .008 x 1 $\frac{1}{16}$ inch bare aluminum interleaved with .004 x 1 $\frac{1}{4}$ inch woven glass tape (e.g. Hess & Goldsmith A-weave).

Secondary coils 33 ----- 9 turns (upper coil) and 8 $\frac{1}{2}$ turns (lower coil) of .011 x 2 $\frac{1}{8}$ inch bare aluminum interleaved with .004 x 2 $\frac{1}{2}$ inch woven glass tape.

Reactor coil 37 (lower) -- 19 $\frac{1}{2}$ turns .018 x 1 $\frac{1}{16}$ inch bare aluminum interleaved with .004 x 2 inch woven glass tape.

Reactor coil 38 (upper) -- 22 turns .011 x 1 $\frac{1}{16}$ inch bare aluminum interleaved with .004 x 1 $\frac{1}{2}$ inch woven glass tape.

The wound core 3 described provides a class H transformer having a maximum operating temperature of

180° C. The woven glass tape provides a nominal dielectric between turns, on the order of about two volts. The woven glass tape therefore acts almost entirely as a mere spacer and the coils effectively have an air dielectric. Although large transformers, such as those used in power transmission, have long used air dielectrics, their use in transformers of the present class has not been considered.

The movable core assembly 6 includes a vertical round shaft 60, the lower end of which extends through the guard screen 21 and the upper end of which extends through the upper cover 25. The shaft 60 is rotatably mounted adjacent the forward face of the core 30 by an upper bracket 61 and a lower bracket 62 on the core 30. The shaft 60 is reduced in the area of each bracket. Each of the brackets 61 and 62 includes a horizontal bracket plate 63 welded to the outboard face of a horizontal reach of frame 30 and extending forward of the frame 30. The lower bracket plate 63 is welded through the guard screen 21. A slot 64 extends rearward from the forward edge of each plate 63. The rearward end of the slot 64 forms a V-shaped seat 65 to receive a journaled reduced section 66 of the shaft 60. The slot 64 is wider than the journaled section 66 of the shaft 60, so that the journaled section 66 makes two point contact with the seat 65. The lower journaled section 66 has a height equal to the thickness of the plate 63, to prevent vertical movement of the shaft 60, and the upper journaled section 66 has a height somewhat greater than the thickness of the plate 63 to prevent the precise distance between the plates 62 from becoming critical for smooth rotation of the shaft 60. A bent keeper piece 67 is held to the plate 63 by bolts 68. The keeper piece 67 is formed like a leaf spring so that a relatively small bearing surface near its free end exerts a strong rearward pressure on the shaft 60 when the bolts 68 are drawn tight.

Welded to the shaft 60 between the support brackets 61 and 62 is a movable core 70. The movable core 70 is a stack of rectangular laminations with a pair of stiffener pieces at the top and bottom of the stack. It is welded together along its sides. The movable core 70 is so proportioned and positioned on the shaft 60 that when it is swung into the window of the frame 30 it is substantially the same depth as the frame 30, its laminations run in the same direction as those of the frame 30, and its upper and lower edges miss the inboard edges of the upper and lower horizontal frame members by about one sixteenth of an inch. A stop bracket 71 is welded to the movable core 70. An upper edge of the stop bracket 71 extends above the movable core 70 and abuts the stiffener 31 when the movable core 70 has been swung completely into the window of the frame 30. A perpendicular upper edge of the stop bracket 71 abuts the stiffener 31 when the movable core 70 has been swung completely out of the window, as shown in broken lines in FIG. 6.

The shaft 60 is made of a nonmagnetic material such as nonmagnetic stainless steel. Because the movable core assembly 6 therefore is affected by the magnetic flux of the frame 30 only through the movable core 70 and the shaft 60 is restrained from vertical or horizontal movement by metal-to-metal contact with the brackets 61 and 62, the movable core assembly 6 is free of vibration in use.

The rotating and locking mechanism 8 is attached to the upper end of the shaft 16, which extends through an aperture 81 in the top cover 25. An arcuate perforation in the top cover 25, outboard of the aperture 81, allows a horizontal shelf 82 to be formed in the sloping top cover 25. A pair of closure pieces in the form of flanged locks 83 and 84 are positioned on the shaft 60 respectively above and below the shelf 82 and are respectively keyed on the shaft in proximity with the shelf 82 by keeper pins 85 and 86 through the shaft.

Each of the locks 83 and 84 includes a hollow stem 87 and a hollow cup 88. The pins 85 and 86 lie in notches 89 in the stems 87 of the locks 83 and 84 and cause the locks 83 and 84 to rotate with the shaft 60. Although the lips of the lock cups 88 preferably touch the shelf 82, they are not held tightly against it by the pins 85 and 86, and the locks 83 and 84 by themselves do not restrict the free rotation of the shaft 60.

A stop 90, having a hollow stem and an enlarged cap 91, is held by a cap screw 95 to the upper end of the shaft 60. A U-shaped cam 92 is also trapped on the shaft 60, between the cap 91 of the stop 90 and the cup 88 of the upper flange lock 83, by the pin 85 which extends through elongate slots 93 in the parallel legs of the cam 92. A handle 94 is screwed to the cross-piece of the cam 92. When the handle 94 is in a generally horizontal position, as shown in FIG. 4, the slot 93 is angled approximately 45° from the vertical, and when the handle 94 is raised the slot 93 approaches the vertical. The surface of the cam in contact with the lock cup 88 is in the form of a smooth arc having a center of curvature below and to the handle side of the center of the slot 93. The edge of the cam 92 which engages the stop cap 91 has a much shorter curved section between two straight sections to provide definite locked (handle down) and unlocked (handle up) positions. The height of the cam, between the stop 90 and the cup 88 of the upper lock 83 is greater, of course, in the locked position than in the unlocked position. Furthermore, the shapes of the upper and lower edges of the cam 92 are such that there is little change in this height near the locked position, and the slot 93 allows sufficient downward motion of the cam 92 relative to the pin 85 to make locking and unlocking relatively smooth and effortless. It will be seen that when the handle 94 is raised, the locks 83 and 84 are not compressed and the shaft 60 and movable core 70 may be swung by turning the handle 94. When the handle 94 is pushed down the shelf 82 of the upper cover 25 is compressed between the lips of the cups 88 of the locks 83 and 84, and movement of the shaft and movable core is prevented. It will also be seen that the elongate slot 93 allows the cam 92 to be self-centering, frees it for some vertical movement in the unlocked position, and allows adjustment of the locking mechanism by adjusting the cap screw 95 above the stop 90. Such adjustment may be desirable after the welder has been in long use, to take up the play caused by wear on the cam 92, stop cap 91 and upper lock cup 88. It nonetheless effectively traps the cam and holds it against lateral movement.

The indicating means 10 include a pointer 100 snapped over the top of the shaft 60 and a selector plate 101 secured to the upper face of the top cover 25.

The pointer 100 has a housing part 102 and a finger part 103, molded as a single unit. The housing part 102 is pivotally mounted on the ends of the upper pin 85 on the shaft 60 by a pair of holes 104 in the sides of the housing part 102. The holes 104 are so placed that the pointer 100 is spaced slightly above the selector plate 101 and can pivot around the pin 85. The housing section 102 is wider than the lock 83 and hides it. An aperture 105 is provided in the rear of the housing part 102 to accommodate the handle 94. The forward upper edge 106 of the aperture 105 is bent rearwardly downward to allow the handle 94 to be pulled up over the top of the housing section 102 of the pointer 100.

The finger part 103 includes a small foot 107 for holding the finger part 103 above the surface of the selector plate 101 and a seat 108 for a clear plastic lens 109.

The selector plate 101 extends below the forward edge 70 of the top cover 25 carries labeling for the output plugs 12 and 13. The output plugs 12 and 13 are for simplicity marked A and B respectively. The portion of the selector plate 101 which lies beneath the sweep of the lens 109 on the pointer 100 is provided with a table 75 which includes a set of colored bands 110. In this illus-

trative embodiment, thirteen bands are provided. The forward edge of each band is labeled either A or B to correspond with the labeling of the "high" and "low" output plugs.

The outer band, labeled A, and the next band, labeled B, carry numbers at spaced intervals along their lengths indicating the amperage output of their respective output plugs at that particular position of the pointer 100. Thus, in this example, when the pointer is in its forwardmost position (rotated counterclockwise) the number on the outer band under the plastic lens 109 is 180, which indicates that the output from the A (high) output plug is 180 amps. This end of the second band is marked 85 to indicate the amperage at the B (low) outlet plug. It will be seen that at this position of the pointer 100 the movable core 70 is completely out of the window of the frame 30 and the stop bracket 71 prevents further counterclockwise movement of the shaft 60. When the pointer 100 has been rotated clockwise to the rearward end of the bands, the indicated amperage on the A band is 85 and on the B band is 30. At this position of the pointer 100 the movable core 70 is rotated completely into the window of the frame 30 and the shaft 60 is restrained from further rotation by the stop bracket 71. The amperage bands thus indicate that a continuous range of amperages from 30 to 180 is provided. The intermediate numbers on the outer two bands are chosen to fall at generally even spacings on the bands and represent ranges of from 25 amps to 5 amps.

The remaining eleven bands are colored to represent the spot color or end color, or both, of commonly used welding electrodes. The rearward (clockwise) end of each band, or set of bands, is labeled with the code number of the electrode having the indicated code color and with the type of material appropriately welded with this type electrode. The bands are divided into segments, or ranges, each of which is marked with a number. The number indicates the diameter of a welding rod which is appropriate to that range. Since each range indicates a particular spread of amperages for a particular outlet plug, indicated by the label at the forward end of that band, turning the pointer to that range automatically provides the proper amperage at the indicated output plug for the electrode chosen.

A user desiring to weld a particular kind of material simply looks at the selector plate to determine the code number or code colors of an appropriate type welding electrode, chooses an electrode of that type in an appropriate size lifts the handle 91 to rotate the pointer 100, sets the position of the pointer 100 at a position somewhere in that diameter range on the appropriate band, and pushes the handle 94 down to lock the movable core 70 in place. He then notes whether this band is labeled A or B and plugs the electrode cable into the appropriate output plug. He does not need to go to a separate source to discover a suggested amperage range for that particular electrode and in fact does not need to know amperages at all.

In this illustrative embodiment, the two bands immediately interior of the amperage bands indicate diameter ranges for E6011 electrodes, used for welding mild steel, from a diameter of $\frac{3}{16}$ " at the upper (counterclockwise) end of the outer A band to $\frac{5}{64}$ " at the lower (clockwise) end of the inner B band. Both of these bands are colored blue to indicate the spot color of E6011 electrodes. The next two bands, also labeled A and B, indicate diameter ranges of E6013 electrodes, also used for mild steel. The bands cover the same ranges as the E6011 bands and are colored brown to indicate the spot color of E6013 electrodes. The next two bands, also labeled A and B, are for machinable cast iron electrodes for welding cast iron. The A band is orange and the B band is blue to indicate the end color and spot color respectively of this electrode. The indicated ranges for these bands are from $\frac{3}{16}$ " to $\frac{3}{32}$ ". The next two bands, also labeled A and B, and colored brown and green respectively, are for hard surface-

ing electrodes having a brown end color and a green spot color. The next two bands, also labeled A and B are for E7024 contact rods having a black end color and yellow spot color. The indicated ranges of these last four bands are discontinuous and cover only portions of the bands. The innermost band, colored red, is labeled A and indicates appropriate ranges for $\frac{1}{8}$ " and $\frac{3}{16}$ " cutting rods having red end colors.

If the user wants to use an electrode not listed on the indicator plate 101, he must consult a table of recommended amperages for that electrode and set the pointer to an amperage on the outer bands in the recommended range. He then checks to see whether the band on which this amperage appears is the A band or the B band, and plugs the electrode cable into the appropriate output plug.

Numerous variations in the welding transformer of this invention, within the scope of the appended claims, will occur to those skilled in the art in light of the foregoing disclosure. For example, it is obvious that one or both of the locks 83 and 84, or the adjacent faces of the upper cover, may be faced with a frictional material, or a washer of frictional material may be interposed between the locks and the upper cover. A suitable cork composition frictional material is sold by Armstrong Cork Company as NC 733 cork friction material. Therefore, if such a frictional material is used and it rotates with the lock, it is included in the term "closure piece;" if it does not, it is included in the term "upper cover." Either lock, or both, may be shaped differently, or omitted altogether. Different indicator bands may be provided. These variations are merely illustrative.

Having thus described the invention, what is claimed and desired to be secured by Letters Patent is:

1. In a variable welding transformer having a vertically aligned rotatable shaft and a movable core mounted on the shaft for rotation therewith, the improvement comprising a sheet metal upper cover, said shaft extending through an aperture in said cover, a radially extending lower bearing surface on said shaft below said aperture, said lower bearing surface having a greater outer diameter than said aperture in said upper cover, a cam pivotally mounted on said shaft above said upper cover, said cam being selectively movable from a release position, in which said shaft is rotatable through at least a predetermined arc, to a lock position, in which said cam holds said upper cover tightly against said lower bearing surface on said shaft.

2. The improvement of claim 1 wherein said lower bearing surface comprises a lower closure piece, and including an upper closure piece between said upper cover and said cam, said upper closure piece having a greater outer diameter than said aperture in said upper cover, each of said closure pieces having an aperture through which said shaft extends; and an abutment on said shaft below said lower closure piece, said lower closure piece resting on said abutment, said cam bearing against said upper closure piece when it is in its lock position for holding said upper closure piece and said lower closure piece tightly against said upper cover.

3. The improvement of claim 1 wherein said upper closure piece comprises a cup, the lip of said cup resting on said upper cover.

4. The improvement of claim 2 wherein said upper closure piece and said cam are both connected to said shaft for rotation therewith by a pivot pin extending through said shaft above said upper cover.

5. In a variable welding transformer having a movable core mounted on a vertically aligned rotatable shaft the improvement comprising a sheet metal upper cover, said shaft extending through an aperture in said cover; a pivot pin in said shaft above said cover; a cam, said cam comprising a yoke part having two parallel vertical sides and a handle part, said parallel sides having a pair of elongate slots in them adapted to receive opposite ends

of said pivot pin, said cam being pivotable about said pivot pin from a lock position to a release position.

6. In a variable welding transformer having a movable core mounted on a vertically aligned rotatable shaft the improvement comprising a sheet metal upper cover, said shaft extending through an aperture in said cover; a pointer mounted on said shaft above said upper cover for rotation with said shaft, and a table on said upper cover, said table including a plurality of colored bands, the color of each band corresponding to a code color of a welding rod.

7. In a variable welding transformer having a rectangular core having an upper and a lower horizontal reach and a movable core mounted on a vertically aligned rotatable shaft the improvement comprising a pair of brackets mounted on said upper and lower horizontal reaches of said core, each of said brackets comprising a horizontal plate, said plate having an aperture in it, said aperture

5

10

15

comprising a V-shaped seat, said seat being adapted to receive a curved surface of said shaft, and a keeper on said brackets, said keeper being adapted to bias said curved surface of said shaft into engagement with said seat.
